UNITED STATES PATENT OFFICE.

JOHN M. YOUNG, OF SAN FRANCISCO, CALIFORNIA.

GRADER.

1,157,279.

Specification of Letters Patent.

Patented Oct. 19, 1915.

Application filed October 21, 1914. Serial No. 867,786.

To all whom it may concern:

Be it known that I, JOHN MARSHALL YOUNG, a citizen of the United States, residing in the city and county of San Francisco and State of California, have invented certain new and useful Improvements in Graders, of which the following is a specification.

The present invention relates to improvements in vegetable graders, and more particularly to an apparatus for sorting or grading asparagus as to size, preparatory to the preserving or cooking of the same for use.

15 The invention has for its principal objects to provide an apparatus which is capable of handling a greater quantity of the vegetable than is possible by the hand grading or sizing now employed, and with less employees, 20 thereby reducing the cost of grading and correspondingly increasing the output of a packing house, one which will automatically cut the asparagus to uniform lengths, and which will grade the cut stalks into sizes according to diameter; one which is automatic 25 in all of its operations, and is thoroughly efficient for the purpose designed.

The invention consists primarily in a plurality of guiding means into which the single stalks of asparagus are deposited, and the guiding means having variable outlet openings which open step by step and permit the asparagus to pass therethrough at different intervals, and preferably into different bins or grade hoppers.

With the above mentioned and other objects in view, the invention consists in the novel construction and combination of parts hereinafter described, illustrated in the accompanying drawings, and pointed out in the claims hereto appended, it being understood that various changes in the form, proportion, size and minor details of construction within the scope of the appended claims may be resorted to without departing from the spirit or sacrificing any of the advantages of the invention.

To more fully comprehend the invention, reference is directed to the accompanying drawings, wherein—

Figure 1 is a top plan view of the improved apparatus. Fig. 2 is a view in side elevation of the apparatus with the table and one of the guide cylinders in section. Fig. 3 is a vertical sectional view through

one of the guide cylinders, disclosing the lower end thereof in closed position above the retaining plate and below the cutting means, and an asparagus stalk positioned in the cylinder. Fig. 4 is a view similar to Fig. 3, but with the discharge end of the cylinder in open position. Fig. 5 is a sectional view taken on line $x-x$ of Fig. 3, with the asparagus stalk removed. Fig. 6 is a sectional view taken on line $y-y$ of Fig. 4, 65 with the asparagus stalk removed.

Referring more particularly to the several views of the drawings, wherein like characters of reference designate corresponding parts throughout the several views, the numeral 1 indicates a suitable base, formed at one side edge with an upstanding overhanging arm 2 which rotatably supports the upper end of a vertically disposed shaft 3, mounted at its lower end in a bearing sleeve 4 extending upwardly from the base 1. The shaft 3 carries a gear 5 which intermeshes with a worm 6 carried by a shaft 7 rotatably supported on the arm 8, and said shaft carries a belt pulley which is rotated by power received from any suitable source.

Keyed to rotate with the shaft 3 is a suitable circular table or support 9 formed adjacent its peripheral edge with a plurality of openings, in each of which is positioned a vertically disposed circular guide cylinder 10, each of which projects downwardly below the underside of the table with its upper edge flush with the upper surface thereof. The lower end of each of said guide cylinders is closed by a plurality of downwardly extending quadrant shaped sections or fingers 11 which taper toward their lower ends, and when in a position to close the lower end of the cylinders lie adjacent the side edges of each other. Said fingers are formed at their extreme lower ends with a cut out portion, which, when the sections are in a position with their side edges in contact form a small circular opening 12 at the extreme lower end thereof. The outer surface of each of said sections or fingers 11 carries an upwardly projected arm 13 which is pivoted, as at 14, to a lug 15 projecting outwardly from the outer surface of the cylinders, and the upper ends of said arms are each connected by a link 16 with a lug 17 carried by a collar 18 surrounding the cylinders and slidably mounted thereon.

A forked lever 19 is pivotally connected

to each collar 18 and said levers are pivotally mounted to the underside of the table, as at 20, and carry on their inner ends rollers 21 which operate in a cam groove 22 formed in the peripheral edge of a suitable stationary circular disk 23 supported on the sleeve 4. The cam groove 22 lies in a horizontal plane, and in the present apparatus is disposed in four different planes, so that as the table rotates the outer ends of the levers 19 will assume four different positions, and vary the outlet end of the tubular guides to four different sizes, the sizes increasing as the table rotates in a counter-clockwise direction from a common feed station.

A suitable supporting plate 24 supported by brackets 25 secured to the arm 2 is positioned a slight distance beneath the lower ends of the fingers 11, controlling the guide cylinders, and extends a short distance on either side of the arm 2, and on said plate rest the lower ends of the stalks of asparagus after being fed into the tubular guides, 25 in an suitable manner, as by an operator.

A suitable knife or cutting member 26, Figs. 2 and 3, is carried above the disk 9 by a bracket 27 adjustably mounted on the arm 2, and said knife severs the projecting ends 30 of the stalks carried in the tubular guides, as the respective guides pass beneath the same on the rotation of the disk. A directing flange 28 is carried on the knife 26 for directing the cut portions of the stalks to 35 one side of the knife to drop into a suitable receptacle 29.

Positioned beneath the table 9, and in the path of rotation of the tubular guides 10, are a plurality of receiving means, each formed 40 of the downwardly inclined troughs 30 terminating in a discharge chute 31 and supported by the legs 32. Each receiving means is adapted to receive a different grade of asparagus, and one of said receiving means 45 is co-extensive with each different plane of the cam groove 22, as in Fig. 1 of the drawings. Power being applied to the band pulley 8 to drive the table 9 in the direction of the arrows—Fig. 1, and an operator positioned at the feed station A, to position a 50 single stalk of asparagus in each guide tube with the tips thereof pointed downwardly, the apparatus operates in the following manner to separate the asparagus into different grades. The tips of the asparagus positioned in the guides will rest on the inner surfaces of the fingers 11 and on the plate 24, and as the table 9 rotates, the butt ends of the stalks will be engaged by the 55 knife 26, and the projecting ends thereof will be severed. As the table 9 rotates, the lower ends of the closure fingers 11 will successively pass over the edge of the plate 24 and should the asparagus stalks, contained 60 in the guide tubes, be of a diameter suffi-

ciently small to pass through the opening 12, the stalk will pass through the same into the first receiving means, which receives the smallest or first grade. The continued rotation of the table will cause the ends of the 70 levers 19 associated with the guide tubes, in the path of movement from the feed station A, to successively pass into a section of the cam groove 22 in a plane below a previous section, which action will cause the fingers 75 11, forming the variable outlet for the tubes, to become slightly separated and increase the size of the opening 12, as in Figs. 4 and 6, which will permit stalks of the next larger size to pass from the tubes into another bin, 80 and constitute the second size or grade. As the table continues to rotate, the ends of the levers 19 will successively pass into sections of the cam groove 22, which lie in a plane lower than a preceding section, until the fingers 11, forming the variable outlets for the 85 respective tubes 10, are successively separated to permit stalks of various sizes to pass therefrom and into their proper receiving means. After the fingers 11 have been separated their full distance to permit the largest size stalk to pass from the guide tubes, the ends of the levers 19 pass into the highest section of the cam groove 22 which is adjacent the feed station A, which causes the 90 lower ends of the fingers to be drawn together, as in Figs. 3 and 5, in which position the guides are adapted to receive fresh stalks for separation. In my apparatus it will be apparent that the variable outlets 95 for the guide tubes are opened to provide an opening a trifle larger as the respective guides are moved from over one receiving means to another, thereby permitting the various sized stalks to pass from their respective guide tubes when the same are in coöperative relation with certain receiving means.

It is to be understood that the supporting table is capable of carrying a plurality of 100 rows of guide tubes, and it is also to be understood that a plurality of feed stations may be provided.

Having thus described my invention, what I claim and desire to protect by Letters Patent is:

1. In an apparatus for the described purpose comprising a vertically disposed tubular guiding means for receiving the material to be graded, a tapered variable outlet 120 downwardly extended from said guiding means and formed of coöperating sections, and means co-acting with said variable outlet for controlling the opening thereof upon the movement of said guiding means.

2. An apparatus for the described purpose, comprising a plurality of vertically disposed tubular open ended guiding means, each adapted for receiving a single article to be graded, a tapered variable outlet 130

- downwardly extended from each of said guiding means and formed of a plurality of coöperating segments, means for receiving the graded articles as the same pass from 5 said guiding means, and means coacting with said variable outlet for controlling the opening thereof as said guiding means successively coöperate with said graded article receiving means.
- 10 3. An apparatus for the described purpose, comprising a plurality of vertically disposed open ended tubular guiding means and a plurality of receiving means, one movable relative to the other, said guiding means 15 each adapted for receiving a single article to be graded, and each receiving means adapted for receiving the graded articles, a tapered variable outlet downwardly extended from each of said guiding means and 20 formed of a plurality of coöperating segments, and means coacting with said variable outlets for controlling the opening thereof on the movement of said guiding and receiving means relative to each other.
- 25 4. An apparatus for the described purpose, comprising a vertically disposed open ended tubular guide member for receiving the articles to be graded, a tapered variable controlled outlet downwardly extended from 30 the guide and formed of a plurality of segments, devices associated with said outlet and carried by said tubular guide for actuating said controlled outlet, and means associated with said devices to control the 35 movements thereof to vary the outlet of the guide proportionately to the size of the article to be discharged therefrom.
5. In an apparatus for the described purpose, comprising a vertically disposed open ended tubular guide for receiving the articles to be graded and provided at its lower end with a tapered variable outlet formed of coöperating segments, and means for operating 40 said segments to vary the outlet of the guide proportionately to the size of the article to be discharged therefrom.
6. In an apparatus for the described purpose, comprising a vertically disposed open ended tubular guide for receiving the articles to be graded and provided at its lower end with a tapered variable outlet formed of coöperating segments, means for operating 45 said segments to vary the outlet of the guide proportionately to the size of the article to be discharged therefrom, devices for receiving the graded article, and mechanism for moving said receiving devices and said guide relative to each other.
- 50 7. In an apparatus for the described purpose, comprising a vertically disposed open ended tubular guide for receiving the article to be graded and provided with a variable outlet, means for cutting articles to be 55 graded to a uniform length while positioned in said guide, and means for varying the 60 outlet of the guide proportionately to the size of the article to be discharged therefrom.
8. An apparatus for the described purpose, comprising a vertically disposed open ended tubular guide for receiving the articles to be graded, a variable controlled outlet for the guide, devices for actuating said controlled outlet, means associated with said devices for controlling the movement thereof to vary the outlet of the guide proportionately to the size of the article to be discharged therefrom, and means for cutting the articles to be graded to a uniform length 65 while positioned in said guide. 70
9. An apparatus for the described purpose, comprising a vertically disposed open ended tubular guide adapted for receiving a single article to be graded and formed at its lower end with a tapered variable discharge opening formed of a plurality of coöperating segments, devices for actuating said segments, and means associated with said actuating devices for controlling the movements thereof to vary the outlet of the 75 guide proportionately to the size of the article to be discharged therefrom. 80
10. An apparatus for the described purpose, comprising a vertically disposed open ended tubular guide adapted for receiving a single article to be graded and formed at its lower end with a variable controlled outlet, devices for actuating said variable controlled outlet, means associated with said devices for controlling the movement thereof to vary the outlet of the guide proportionately to the size of the article to be discharged therefrom, devices for receiving the graded article, mechanism for moving said receiving devices and guide relative to each other, and means for cutting the ends of the 85 articles projected from the upper end of said guide. 90
11. An apparatus for the described purpose, comprising a rotatable support, a plurality of vertically disposed open ended tubular guides carried thereby and each adapted to receive a single article to be graded, a variable controlled outlet for the lower end of said guides and formed of a plurality of coöperating segments, a plurality of receiving means below the path of movement of said guides for receiving the graded articles, and associated instrumentalities for operating said segments to vary the outlet of each 95 of said guides as the same are moved into cooperative relation with each of said receiving means. 100
12. An apparatus for the described purpose, the same comprising a movable support, an open ended tubular guide carried thereby and adapted to receive a single article to be graded, a plurality of fingers pivotally mounted at the lower end of said guide and forming a variable discharge 105 110
13. An apparatus for the described purpose, the same comprising a movable support, an open ended tubular guide carried thereby and adapted to receive a single article to be graded, a plurality of fingers pivotally mounted at the lower end of said guide and forming a variable discharge 115 120
14. An apparatus for the described purpose, the same comprising a movable support, an open ended tubular guide carried thereby and adapted to receive a single article to be graded, a plurality of fingers pivotally mounted at the lower end of said guide and forming a variable discharge 125 130

opening, a collar slidable on said guide, link connections between said fingers and said collar, and a lever associated with said collar and operated on the movement of said support for operating the fingers to vary the outlet of the guide.

13. An apparatus for the described purpose, the same comprising a rotatable support, a plurality of vertically disposed open ended tubular guides carried thereby and each adapted to receive a single article to be graded, a plurality of fingers pivotally mounted at the lower end of each of said guides and forming a variable discharge opening, a collar slidable on each of said guides, link connections between the collar and fingers of the respective guides, a plurality of independent receiving means be-

low the path of movement of said guides, cutting means above said support for severing the ends of the articles to be graded projected above the upper ends of said guides, a pivoted lever associated with each of said rings, and a stationary cam for operating said levers on the movement of said table 25 for operating the fingers to vary the outlet of the guides as the same are moved into cooperative relation above each of the receiving means.

In testimony whereof I have signed my 30 name to this specification in the presence of two subscribing witnesses.
